ABSTRACT OF THE DISCLOSURE

A headrest forming method including the steps of inserting an open-ended cover sleeve that incases an interior cushion into a close fitting hollow shell and turning an end portion thereof out over the edge of the shell to form a turnback and back along the exterior of the shell. Then stretching a sized endless elastic band over the turned back portion and folding the turned back portion forwardly over the band and inwardly over the end of the shell. Thereafter, placing the cover over the inwardly turned portion and sealing it thereto and also sealing the inwardly turned portion to the turnback to seal the band in the end portion to define the welt. Then upturning the welt by rolling it off the end of the shell.

BACKGROUND OF INVENTION**Field of invention**

The present invention relates generally to heat sealed cushions and more particularly to a method for attaching a headrest end cover and for forming a peripheral welt therearound.

Description of prior art

Presently existing headrests such as that shown and described in Patent No. 3,245,719, issued Apr. 12, 1966, are generally made without peripheral end welts and those which are made with such welts are relatively expensive to manufacture. Since the interior cushion must be installed in the cover sleeve before the closing end cover is attached it is difficult to form a peripheral welt in the closing end cover attaching seam.

SUMMARY OF INVENTION

Accordingly it is an object of the present invention to provide a convenient method for attaching the closing end cover of a headrest and forming a peripheral welt therearound.

It is a further object of the invention to provide a method of the type described that employs heat to form the seal between the cover and sleeve.

It is another object of the invention to provide a method of the type described wherein the end cover is presized such that its peripheral edge is concealed beneath the welt in the finished headrest.

It is a more particular object of the invention to provide a method comprised of the steps of inserting a cushion-containing open-ended cover sleeve into a close fitting open-ended hollow shell and turning a portion of the sleeve adjacent the open end out over the edge of the shell to form a turnback and back along the exterior of the shell to form a return. Then stretching a sized endless elastic band over the return and folding said return forwardly over the exterior of the band and inwardly to form a border overlying the turnback. The cover is then placed over the open end of the sleeve with its periphery overlying the border and is sealed thereto. The border is also sealed to the turnback thus sealing the band in the turnback to form the welt. The finished headrest is then

2

removed from the shell by upturning the welt and sliding it therefrom.

Other objects and features of the invention will become apparent from consideration of the following description taken in conjunction with the accompanying drawings.

BRIEF DESCRIPTION OF THE DRAWINGS

FIG. 1 is a perspective view of a shell employed in a preferred method embodying the present invention;

FIG. 2 is a horizontal sectional view taken along the lines 2—2 of FIG. 1 and showing the shell fitted around a headrest;

FIG. 3 is an elevation view, in smaller scale, of the shell shown in FIG. 1, a headrest being shown extending therefrom;

FIG. 4 is a partial elevational sectional view, in enlarged scale, taken along the lines 4—4 of FIG. 3;

FIG. 5 is a partial vertical sectional view, in enlarged scale, taken along the lines 4—4 of FIG. 3, the elastic band being shown in position;

FIG. 6 is a partial vertical sectional view, in enlarged scale, taken along the lines 4—4 of FIG. 3, the cover being shown in place;

FIG. 7 is a partial vertical sectional view taken along the lines 7—7 of FIG. 5;

FIG. 8 is a reduced perspective view of a headrest manufactured by a method embodying the present invention; and

FIG. 9 is a partial vertical sectional view, in enlarged scale, taken along the lines 9—9 of FIG. 8.

DESCRIPTION OF THE PREFERRED EMBODIMENT

Referring to the drawings, FIG. 8 shows a completed headrest H, manufactured by the method of present invention. The headrest H generally includes an elongated cylindrical foam rubber cushion 11 that is covered by an open-ended cover sleeve, generally designated 13, and a pair of like end covers, one of which is shown at 15; the headrest being mountable by a mount 16. In making the headrest H one of the end covers 15 is attached to one end of the sleeve 13, the cushion 11 forced into the sleeve and an open-ended longitudinally-hinged shell 17 buckled over the sleeve 13. The portion, generally designated 19, adjacent the open end of the sleeve is turned outwardly and back on the shell 17 and an elastic band 21, as shown in FIG. 5, is fitted thereover. The end portion 19 is then folded back over the elastic band 21 to define a welt, generally designated 23, and inwardly over the top edge of the shell 17. The cover 15 is placed over the inwardly folded sleeve and sealed thereto and at the same time the overlying layers of sleeve are sealed together to seal the elastic band 21 in place.

More particularly, the preliminary steps of constructing the headrest H are similar to those described in the earlier patent, 3,245,719, including forming the cylindrical cover sleeve 13 by heat-sealing opposite longitudinal ends of a rectangular sheet of heat sealable plastic together.

The mount 16 includes an elongated bar 29 having a pair of right angle brackets 31 attached near opposite ends thereof and is inserted in the sleeve 13 and the ends of the brackets 31 extended outwardly through spaced holes in the sleeve. One end of the sleeve 13 is then covered by an end cover 15 of heat-sealable plastic and a welt 35 formed by the sealing joint. Since the cushion 11 has not yet been installed the sleeve 13 can be turned inside out at this time and the welt 35 forming seal made in a conventional manner, or, if desired, in the same manner as described below for forming the welt 23.

The cushion 11 includes a longitudinal slit 37 that

extends radially into the center from one periphery for receiving the mount bar 29. The cushion is inserted in through the open end 39 of the sleeve 13 by compressing the cushion radially inwardly and sliding the sleeves 13 thereover. Since the cushion 11 is readily compressible the bar 29 can be properly positioned in the slot 37 after the sleeve 13 has been fitted thereover.

The shell 17 comprises two semicylindrical halves 41 that are hinged together on one side by a longitudinal piano-type hinge 42. The free sides of the halves are fastenable together by conventional buckles 43 and include confronting recesses 44 that cooperate to receive the brackets 31 when the shell 17 is closed. A band-receiving groove 45 is machined near the upper end of the shell 17 and an access groove 47 is machined immediately therebeside. A plurality of radial grooves 49 are cut across the edge 51 of the shell 17 to provide more effective heat-sealing, as shown in FIG. 7. The open shell 17 is placed around the cushion-containing sleeve 13 and buckled with the sleeve end portion 19 and cushion 13 extending therefrom. The sleeve end portion 19 is then folded out over the shell edge 51 to form a turnback 53 and back along the exterior of the shell to form a return 55 that overlies the grooves 45 and 47 as shown in FIG. 4.

The band 21 is then stretched over the return 55 pressing the underlying portion into the groove 45 as shown in FIG. 5. The free end of the return is then grasped by inserting the tips of the finger into the access groove 47 and is folded back over the band 21 and inwardly over the shell edge 51 to form an annular border 59 overlying the turnback 53 as shown in FIG. 6. The presized circular end cover 15 is then placed over the end of the sleeve 13 with its peripheral portion overlying the annular border 59 as shown in FIG. 6. The central portion of the cover 15 is pressed downwardly to longitudinally compress the cushion 13 even with the end of the shell 17 and its annular peripheral area is pressed against the shell edge 51 by a heat-sealing ring 61 having an annular abutting surface that complements the annular edge 51. Electric current is then passed through the plate 61 and shell 17 causing the pressed annular area of the cover 15, border 59 and turnback 53 to act as a dielectric, thus heating the edge 51 and causing the adjacent plastics to be heat-sealed together. This provides a circular heat seal between the cover 15, border 59 and turnback 53 thus sealing the cover to the end of the sleeve 13 and sealing the band 21 within the return 55 to define the welt 23, as shown in FIG. 6. The plate 61 is then removed and the welt 23 upturned by rolling it out of the groove 45. Finally, the shell 17 is unbuckled and the finished headrest H removed therefrom.

The cushion 13 will then expand axially against the end cover 15 to force its central portion axially outwardly thus forcing the portion 63 adjacent the welt 23 to assume a contour abutting the radial inner side of the welt 23 to conceal the peripheral edge 65 of the end cover, as shown in FIG. 9. By utilizing the presized cover 15, the necessity of finish trimming is avoided because in the finished joint or seal the peripheral portion 65 of the end cover 15 will be concealed beneath the welt 23.

From the foregoing it will be seen that the method of this invention provides an easy and inexpensive means for attaching the closing end cover 15 of a headrest H and forming a welt 23 to give the headrest an aesthetic appearance.

Various modifications and changes may be made with regard to the foregoing detailed description without departing from the spirit of the invention or the scope of the following claims.

I claim:

1. The steps in a method for attaching the end cover of a headrest and forming a peripheral welt therearound, said headrest being of the type that includes an open-ended sleeve encasing an interior cushion, a sized endless elastic band and an end cover, said steps comprising: inserting said open-ended sleeve into a close fitting open-ended hollow shell and turning an end portion thereof out over the edge of said open end of said shell to form a turnback and back along the outer surface of said shell to form a return; stretching said elastic band around said shell and over said return; folding said return back over the outer surface of said band and inwardly over said edge of said shell to form a border overlying said turnback; placing said cover over said open end of said shell with its periphery overlying said border and sealing said cover to said border and said border to said turnback thereby sealing said band in said turnback to define said welt; and upturning said welt by thereafter rolling it off said open end of said shell and removing said headrest from said shell.

2. A method as set forth in claim 1 wherein said cover, border and turnback are heat sealed together.

3. A method as set forth in claim 1 wherein said shell is of electrically conductive material and said sealing step includes placing an electrically conductive plate over said end of said shell overlying said cover and conducting electrical current therethrough and through said cover, border, turnback and shell.

4. A method as set forth in claim 1 that includes a step before said step of sealing said cover to said border of cutting said cover to a size such that its peripheral edge is concealed by said welt when said welt is upturned.

5. A method as set forth in claim 1 wherein said headrest is of the type that includes an elongated internal cushion in said sleeve and said method includes a step for compressing said cushion longitudinally into said sleeve and maintaining it compressed while said cover is sealed, thereby causing said cover of the finished headrest to be pressed firmly outwardly by said cushion.
